DEMOUNTABLE REVOLVING SHELF ASSEMBLY
FOR KITCHEN CABINETS AND THE LIKE

Robert A. Jorgensen, Edmonds, Wash., assignor to Washington Steel Products, Inc., Tacoma, Wash., a corporation of Washington

Application April 13, 1953, Serial No. 348,418

2 Claims. (Cl. 211—139)

This invention relates to a demountable revolving shelf assembly of the class commonly known as "Lazy Susans" for installation in kitchen cabinets and the like. It also relates to a rotary shelf-supporting bearing assembly for mounting and supporting such shelves.

It is a primary purpose of the present invention to provide a revolving shelf assembly which is easily installed even in cabinets which are difficult of access.

It is another object of this invention to provide a revolving shelf assembly which is applicable to installation in cabinets of a wide variety of designs and dimensions.

Another object of this invention is the provision of a revolving shelf assembly which is safe and sure in its operation.

Another object of this invention is the provision of a revolving shelf assembly which is readily demountable for various purposes, such as its temporary removal, the affixation of shelves of different dimensions or design, or the alteration of the surrounding cabinet work.

Still a further object of this invention is the provision of a revolving shelf assembly which may be easily mounted in precise alignment so that maximum efficiency of operation is obtained.

The manner in which the foregoing and other objects of this invention are accomplished will be apparent from the accompanying specification and claims considered together with the drawings wherein:

Figure 1 is a view in perspective of a typical revolving shelf assembly of the presently described class;

Figure 2 is a view in side elevation partly broken away illustrating the manner of mounting the presently described revolving shelf assembly;

Figure 3 is a view in side elevation partly broken away illustrating the presently described revolving shelf assembly in its operative position; and

Figure 4 is a detail sectional view taken along lines 4—4 of Figure 3.

As is apparent from Figure 1, the revolving shelf assembly of this invention is adapted for installation in corners, for example, of kitchen cabinets represented generally at 10. The assembly may include a central post 12, rotatably mounted between a pair of vertically spaced apart support members 14, 16. On the post are a plurality of cut away, spaced shelves 18, 20, 22 suitably mounted as by means of collars 23.

To the cut away portions of the shelves are affixed a pair of edge abutting face panels 24, 26. Thus the assembly may be adjusted to a first position wherein shelves 18, 20, and 22 are brought to the front, making them accessible, and to a second position in which panels 24, 26 are brought to the front, aligned with the other front panels of the cabinet. As a result, the assembly may be employed to convert inaccessible corner areas to readily accessible, useful storage space.

The manner of mounting the presently described revolving shelf assembly is illustrated in Figures 2, 3 and 4. Affixed to the lower structural member 14 is a pivot pin

2

or spindle 28 provided with a base plate 30. The upper surface of pivot pin 28 is recessed or dished to accommodate a ball bearing 32.

To rotatably mount post 12 on pivot pin 28 there is provided a thimble 34 having at its open end an annular flange 36. Thimble 34 is dimensioned to nest over pivot pin 28 and to rest on ball bearing 32. The lower end of post 12 is hollow and dimensioned to nest over thimble 34, resting on flange 36. Free rotatability thus is obtained even though a substantial load is placed upon shelves 18, 20 and 22.

A second pivot pin 40, provided with base plate 42 and an annular groove 44 a spaced distance from its end is mounted on the upper support member 16, substantially aligned with pivot pin 28 and with post 12 when the latter is vertical. Pivot pin 40 and post 12 are dimensioned relative to each other so that when the post rests on flange 36 of thimble 34 there is a clearance distance between the top of the post and the lower edge of pivot pin 40. Accordingly, as is illustrated in Figure 2, the post may be readily moved from a first position in which it is not aligned with pin 40 to a second position in which it is aligned therewith.

Means are provided for rotatably mounting the upper end of post 12 and for releasably connecting the post to upper pivot pin 40. Such means comprise the bushing or sleeve 46 having an annular flange 48.

Bushing 46 is dimensioned to nest within the upper hollow end of post 12 with flange 48 resting thereupon. The bore 46' of bushing 46 is of such a dimension as to rotatably enclose that portion of pivot pin 40, which is below groove 44. Hence when bushing 46 is in its operative position nesting within the bore of post 12, the post and the shelves which it supports are freely rotatable between the support members.

Means then are provided for releasably maintaining the bushing in its operative position interconnecting pivot pin 40 and post 12 since during operation of the assembly, particularly if an uneven load is placed upon it, the bushing might work upwardly, releasing the post with catastrophic results. Accordingly, in the illustrated embodiment, keeper means are provided in the form of a keeper spring 50 dimensioned to bed in groove 44 on the pivot pin.

The revolving shelf assembly of this invention is easily and accurately installed and operated. To install the assembly, pivot pins 28 and 40 first are affixed to their respective support members in substantial alignment with each other. Ball bearing 32 is placed in the recess of pin 28 and thimble 34 placed thereover. Post 12, which may comprise standard thin wall electrical conduit cut to length, then is placed over thimble 34 until it rests on flange 36 thereof.

Bushing 46 next is slipped over pin 40 and post 12 shifted to a vertical position, after which the bushing is dropped into the opening at the top of the post. After checking the operation of the assembly, post 12 may be removed and shelves 18, 20 and 22 or their equivalents mounted thereon in any desired manner, as by means of collars 23. The assembly procedure then may be repeated, keeper spring 50 being inserted in groove 44 when all the parts are in place. This will maintain them securely in their proper relationship to each other until it is desired to remove the post and shelves for some purpose.

Thus it will be apparent that by the present invention I have provided a revolving shelf assembly and a supporting bearing assembly therefor which is easily and accurately installed and operable in a variety of installations. Also, it operates freely and is readily demountable when desired. Finally, it is safe in operation since the keeper means prevents the inadvertent escape of bushing 46 from post 12 with consequent upsetting of the shelves.

It is to be understood that the form of my invention herewith shown and described, is to be taken as a preferred example of the same, and that various changes in the shape, size and arrangement of parts may be resorted to, without departing from the spirit of my invention, or the scope of the subjoined claims.

Having thus described my invention, I claim:

1. An easily assembled demountable revolving shelf assembly comprising a pair of vertically spaced structural supports, first pivot means mounted on the inner side of the lower of said supports, a vertical supporting post rotatably mounted on and supported by said first pivot means, shelves surrounding and supported by said post, second pivot means mounted on the inner side of the upper of said supports in axial alignment with said first pivot means, the end of the post remote from said first pivot means being tubular, the post being dimensioned so that said remote end is spaced from the inner end of said second pivot means when said post is rotatably mounted on and supported by said first pivot means, said second pivot means comprising a spindle projecting downwardly from said upper support, connecting means slidably disposed on said spindle, said connecting means having a lower portion dimensioned to fit within the bore defined by the tubular portion of said post and an upwardly disposed outwardly extending flange limiting the movement of said connecting means within the bore of said post, said connecting means being longer than the space between

5 the inner end of said spindle and the said remote end of said post and shorter than the space between the upper support and the remote end of the post, keeper means intermediate the length of said spindle and acting as a stop against the upper portion of said connecting means to retain the lower portion of said connecting means within

10 said bore and securing means movably securing said keeper means to said spindle to permit said connecting means to be slid out of engagement with said post and to permit removal and insertion of said post while said post is supported by said first pivot means.

2. A revolving shelf assembly as recited in claim 1 in which said securing means includes an annular groove positioned intermediate the length of said spindle and said keeper means is constituted by a spring releasably secured about said spindle in the groove thereof.
